UNITED STATES PATENT OFFICE.

GEORGE HENRY HILLYER, OF DULUTH, MINNESOTA.

MOTOR-HANDLE FOR TOOLS.

SPECIFICATION forming part of Letters Patent No. 714,581, dated November 25, 1902.

Application filed April 29, 1902. Serial No. 105,213. (No model.)

To all whom it may concern:

Be it known that I, GEORGE HENRY HILLYER, a citizen of the United States, residing at Duluth, in the county of St. Louis and State of Minnesota, have invented certain new and useful Improvements in Motor-Handles for Tools; and I do hereby declare the following to be a full, clear, and exact description of the invention, such as will enable others skilled in the art to which it app pertains to make and use the same.

This invention relates to improvements in tool-handles, and particularly to a handle provided with a contained motor.

15 The object in view is the production of a tool-handle designed to carry any suitable tool and to contain a motor for driving the tool, the word "motor" being meant in its broadest sense and indicating any type of engine, whether electric or otherwise.

A further object is the provision of such a handle having means for changing the speed of the tool carried thereby.

With these and other objects in view the invention consists in certain novel constructions, combinations, and arrangements of parts, as will be hereinafter fully described and claimed.

In the accompanying drawing, the figure 30 represents a longitudinal central section taken through a tool-handle embodying the features of the present invention.

In order to facilitate access to the interior of the present tool-handle, I preferably employ, as seen in the accompanying drawing, suitable hollow sections, as 1 and 2, threaded or otherwise suitably, preferably detachably, secured together. Arranged longitudinally

within these sections is a driving-shaft, as 3, 40 operated by a magnet, as 6, surrounded by field 7, said shaft having a journal 4, finding a bearing in an elongated block, as 5, and mounted to slide longitudinally therein for a short distance, an electric current being sup-

plied to the parts, preferably through conductors passed through any suitable insulating-block 8 in the end of section 1. Near the opposite end of shaft 3 is provided a bracket, as 16, in which said shaft is slidably mounted,

50 said shaft carrying a rigid arm, as 17, fixed at its inner end to a sleeve surrounding shaft 3 and permitting the same to rotate freely,

the sleeve being fixed against longitudinal movement, so that movement of the arm 17 will shift shaft 3 longitudinally, said arm 17 extending through a longitudinal slot, as 18, in section 2, and being preferably formed with an operating-button, as 19, at its outer end. A shaft, as 11, finds bearing at one end in a portion of bracket 16 and at the other 55 end in the end of section 2, said shaft being arranged longitudinally of said section and carrying a comparatively large gear-wheel, as 10, and a comparatively small gear 13. A connecting-rod, as 14, extends through the 60 end of section 2 in axial alinement with shaft 3, being formed within said section with a comparatively large gear-wheel, as 20, meshing with gear 13, and outside the end of said section with an annular flange, as 21, for retaining the same against longitudinal movement. The outer end of rod 14 is formed with a tool-carrying head, as 15, and the inner end is formed with a squared or polygonal notch, as 22. The shaft 3 is provided with a 65 fixed comparatively small gear-wheel, as 9, designed when said shaft is at one extreme of its longitudinal movement to mesh with gear 10, and the shaft is further provided with a square or polygonal block, as 12, designed to fit snugly into notch 22 when the 70 said shaft is at the other extreme of its longitudinal movement, the said gear being out of mesh when the block is in said notch and the block being out of said notch when the 75 gear-wheels are brought into mesh. It will be apparent that by simply sliding button 19 from one end to the other of slot 18 the speed of head 15 may be increased or decreased, as desired.

Having thus fully described my invention, what I claim as new, and desire to secure by Letters Patent, is—

1. A tool-handle comprising a suitable hollow body, a motor arranged therein, a shaft 95 slidably connected with said motor, tool-carrying means receiving movement from said shaft, gearing connecting said shaft with the tool-carrying means when at either extreme of its movement, and means for shifting said 100 shaft, substantially as described.

2. A tool-handle comprising a suitable hollow body, a motor arranged longitudinally therein, a longitudinal shaft slidably con-

nected with said motor, tool-carrying means receiving movement from said shaft, means for altering the speed of said tool-carrying means, with the shifting of said shaft, and means for shifting the shaft, substantially as described.

3. A tool-handle comprising a suitable hollow body, a shaft mounted therein, a motor for rotating said shaft, a tool-carrying rod in axial alinement with said shaft, a chain of gearing for imparting movement from said shaft to said rod when the shaft is in position, and means for establishing direct communication of movement of the shaft to the rod, substantially as described.

4. A tool-handle comprising a suitable hollow body, a shaft mounted therein, a motor for rotating said shaft, a tool-carrying rod extending through one end of said handle in axial alinement with said shaft, means limiting said rod against longitudinal movement, and means for shifting said shaft longitudinally for bringing the same into contact with said rod, substantially as described.

5. A tool-handle comprising a suitable hollow body, a shaft mounted therein, a motor for rotating said shaft, a tool-carrying rod extending through one end of said handle in axial alinement with said shaft, and provided with means for preventing longitudinal movement, a polygonal notch being formed in the inner end of said rod, a polygonal block on the corresponding end of said shaft, and means for shifting said shaft for causing said block to enter said notch, substantially as described.

6. A tool-handle comprising a suitable hollow body, a shaft slidably mounted therein, means extending outside said body for slid-

ing said shaft, means for rotating said shaft, tool-carrying means retained by said handle, and means for imparting movement from said shaft to said handle in a degree of speed relative to the adjusted position of the shaft, substantially as described.

7. A tool-handle comprising a suitable hollow body, a shaft mounted therein, a motor for rotating said shaft, tool-carrying means retained by said handle, a chain of gearing for imparting motion from said shaft to said tool-carrying means, and means extending outside the body for adjusting said shaft for breaking connection with said gearing and imparting motion directly from the shaft to said tool-carrying means, substantially as described.

8. A tool-handle comprising a suitable hollow body, a shaft mounted therein, a motor for rotating said shaft, a tool-carrying rod extending through one end of said handle and provided with a gear-wheel at its inner end, and a flange outside the end of said handle for limiting the longitudinal movement of said rod, said rod being in axial alinement with said shaft and provided with a polygonal notch in its inner end, a polygonal block carried near the inner end of said shaft, a chain of gearing for connecting said shaft with the gear-wheel of said rod, and means for shifting said shaft for breaking connection thereof and seating said block in said notch, substantially as described.

In testimony whereof I hereunto affix my signature in presence of two witnesses.

GEORGE HENRY HILLYER.
